UNITED STATES PATENT OFFICE.

WILLIAM C. MAYO AND JOHN HOULEHAN, OF EL PASO, TEXAS, ASSIGNORS OF ONE-THIRD
TO GEORGE E. BRIGGS, OF BARSTOW, TEXAS.

CLEANING APPARATUS.

No. 923,547.

Specification of Letters Patent.

Patented June 1, 1909.

Application filed February 24, 1908. Serial No. 417,383.

To all whom it may concern:

Be it known that we, WILLIAM C. MAYO and JOHN HOULEHAN, citizens of the United States, residing at El Paso, in the county of 5 El Paso, State of Texas, have invented a new and useful Cleaning Apparatus, of which the following is a specification.

This invention has reference to improvements in cleaning apparatus, and is directed 10 more particularly to the cleaning head and depositing chamber wherein the air is relieved of the dirt and dust removed from the articles cleansed.

The object of the present invention is to 15 provide means whereby the dirt and dust may be dislodged from the articles to be cleansed by the direct action of a stream of air forcibly blown against the articles, and the dust laden air then passes through a suitable depositing chamber or the dirt may be 20 dislodged from the articles by producing a vacuum so that the external air is caused to flow through the article to be cleansed and so dislodge the dirt and dust which is then 25 conveyed to a suitable depositing chamber, or any combination of these two operations may be used at will.

In accordance with the present invention 30 there is provided a suitable air pump driven by any suitable type of motor, whether the same be an electric motor or a water motor or an explosive engine, but generally an electric motor will be employed. In connection with the air pump there is a reservoir upon 35 which is secured a depositing chamber through which the refuse laden air has a tortuous passage so that the major portion of the refuse taken up by the air from the article to be cleansed is deposited in such passage. However, some of the lighter particles 40 may still remain suspended in the air, and to remove such particles the depositing chamber is provided with a series of graded screens ultimately opening into a water chamber through which the air is caused to 45 pass to be thoroughly washed by the action of the water. This is an important precaution since the air which has become laden with dust and dirt from its action upon the 50 article to be cleansed is again passed through the pump and any grit which might be carried by such air to the pump would be injurious to the pump cylinders and valves.

In connection with the depositing chamber 55 there is provided a cleaning head which

may be applied directly to the articles to be cleansed, and this cleaning head has communication directly with the pump or with a reservoir into which the pump discharges air under pressure, so that a stream of compressed air may when desired be directed upon the article to be cleansed. The cleansing head has also communication with the depositing chamber, which latter is likewise in communication with the suction side of the pump, so that air is drawn from the article to be cleansed and carries the dislodged refuse to the depositing chamber to be there relieved from its load of refuse.

The invention will be best understood by 70 consideration of the following detail description taken in connection with the accompanying drawings forming part of this specification, in which drawings,—

Figure 1 is a central section, with parts in 75 elevation, of the depositing chamber and reservoir supporting the same and also showing a pumping mechanism in elevation. Fig. 2 is a plan view of the cleansing chamber. Fig. 3 is a central section through the 80 cleansing head. Figs. 4 and 5 are elevations of the cleansing head taken at right angles to each other. Fig. 6 is an elevation, with some parts in section and other parts broken away, of the complete apparatus, the showing 85 being somewhat conventional.

Referring to the drawings, and more particularly to Figs. 1, 2, and 6, there is shown an air pump 1, which showing may be considered as indicative only of an air pump 90 capable of continuous operation, when so desired for supplying air under pressure to the reservoir 2. The air pump is not shown in detail since it forms the subject-matter of another application for Letters-Patent. 95 The air pump is in communication with the reservoir 2 by means of a suitable pipe 3.

The reservoir 2 may be in the form of a cylinder, as indicated, the upper end of which is formed with an outwardly-extending annular flange 4 and with a top or cover 5^a secured to the reservoir, and the whole reservoir is constructed to stand a working pressure which may reach one hundred pounds or more to the square inch.

Mounted upon the reservoir is a casing 5 constituting the cleansing chamber, and this casing is provided at the lower end with a lateral annular flange 6 matching the flange 4 of the reservoir. Any suitable means for 110

connecting these parts together may be employed, and a convenient means is shown comprising a bolt 7 hinged to the reservoir 2 beneath the flange 4 and provided with a wing-nut 8, while the flanges 4 and 6 are each suitably slotted so that the hinge bolt may be turned upon its pivot to enter the slots in the two flanges, which slots are made to match, and the two flanges may be brought together with any desired pressure by the wing nuts. This is a familiar type of latch connection and need not be further considered, except to state that an appropriate number of such latches are used. Furthermore, there is interposed between the top of the reservoir 2 and the bottom of the depositing chamber 5 a suitable packing 9 which may be of rubber or gum or other material which will answer the purpose. The bottom of the chamber 5 is closed by a bottom plate 10 having an upturned peripheral flange 11. The plate 10, however, is not fastened to the walls of the chamber. Formed on and extending downward from the inner face of the top of the chamber 5 are a number of parallel baffle plates 12 which are also formed integral with the side walls of the chamber as indicated in Fig. 2. Formed on the bottom plate 10 are other parallel spaced baffle plates 13 arranged to engage the side walls of the casing 5, at points intermediate of the baffle plates 12. Furthermore the baffle plates 12 are not quite as deep as the depth of the casing 5 and the baffle plates 13 do not reach quite to the upper wall or top of the casing 5. Consequently there is a tortuous passage from one end of the series of baffle plates to the other end. The baffle plates begin near one end of the casing 5 but do not reach quite to the other end. At the last-named end there is formed on the casing 5 a lateral wall 14 spaced some distance from the corresponding end of the casing and joined to the said end wall of the casing by a horizontal bottom portion 15. Projecting down from the top of the casing into the chamber formed between the wall 14 and the corresponding end of the casing is still another baffle plate 16 reaching to nearly the bottom of the compartment formed between the wall 14 and the end wall of the casing. This compartment is reached through an opening 17 in the top of the casing closed by a suitable plug 18 which may be a screw plug or cap with milled edges for convenience of manipulation. Water is poured into the compartment until it extends a considerable distance above the lower edge of the baffle plate 16. Between the wall 14 and the last baffle plate 12 of the series of baffle plates are arranged a number of horizontal screens 19 of gradually increasing fineness of mesh from the lowermost screen to the uppermost, which latter is placed near the top of the wall 14, the upper edge of the said wall not reach-

ing quite to the bottom face of the top of the casing 5.

Entering the water chamber near the upper end thereof is a pipe 20 which may terminate in a nozzle shaped to receive the end of a flexible pipe 21, the other end of which is adapted to another nozzle 22 on the end of a pipe 23 fast by a bracket 24 to reservoir 2 and leading to the intake of the pump. This structure is shown in Fig. 1. Secured to the reservoir 2 is a casting 25 formed with a flange 26 engaging the walls of the casting while a neck 27 extends through a suitable perforation in the casting and it is then headed over, as shown at 28, to form a tight connection. This showing is largely conventional since any other type of connection may be used, but so far as the understanding of the present invention is concerned the connection as shown and described will answer. The casting 25 is formed with a central through passage 29 leading from the reservoir 2 to a nipple 30 receiving one end of a flexible pipe 31 which may be in the form of a small bore hose. The casting 25 is also formed with a passage 32 concentric with the passage 29 and extending through a nipple 33 adapted to receive a larger hose 34 inclosing the small hose 31. The casting 25 is formed with a lateral neck 35 communicating with the passage 32 and terminating in a bell 36. In the casting 25 are mounted three valves 37, 38 and 39. The valves 37 and 39 are provided with axial passages 40 communicating with the external air and from these passages each valve has a lateral extension 41 extending to its periphery. The valve 38 has a three-way passage 42 through it. The passage 41 of the valve 37 may be brought into communication with the passage 29 by a port 43, and the passage 41 of the valve 39 may be brought into communication with the passage 32 through a port 44. The valve 38 is so located that the three-way connection may be set to form a continuation of the passage 29 or to entirely close said passage or to move the interior of the reservoir 2 into communication with the external air through another passage 45 in the casing 25.

The chamber 5 at the end remote from the pipe 20 is connected to a conduit 46 which may be either round or other shape but is shown as rounded, and this pipe is supported by a bracket 47 fast on the side wall of the casing 5. The lower end of the conduit 46 is formed with a flange 48 snugly fitting the bell 36, and between this flange 48 and the bottom of the bell 36 there is interposed a rubber or gum or other suitable washer or packing 49.

Referring now to Figs. 3, 4 and 5, there is shown a cleaning head composed of two concentric bells 50, 51 spaced apart and joined together by web sections 52. The bell 51 is

shorter than the bell 50 and of less diameter, and its lower edge 53 is rounded, as indicated, this lower edge terminating above the lower edge of the bell 50. Projecting centrally upward from the bell 51 is a neck 54 terminating at the upper end in the shoulder 55 from which rises a screw nipple 56. The upper end of the bell 50 is also formed with a shoulder 57 from which rises a threaded collar 58 surrounding but spaced from the nipple 56 of the neck 54. Extending centrally through the neck 54 is a passage 59 counter-bored at its lower end, as at 60, to receive the threaded end 61 of a nozzle 62 provided with an annular shoulder 63 to abut against the lower face of the top of the bell 51, and the lower or outlet end of the nozzle 62 is contracted, as shown at 64, while the mouth of this contracted portion may be expanded, as shown at 65. In the practical embodiment of the invention a number of nozzles 62 of various lengths and sizes of orifice will be provided and consequently the showing of the drawing is to be taken as illustrative only.

The bottom of the bell 50 is formed with an inwardly-directed annular flange 66, at the periphery of which is a rabbet 67 the walls of which include a more or less acute angle. Seated in this rabbet and against the under face of the flange 66 is an annular soft rubber facing 68 which may be sprung into the rabbet 67 and so held.

The end of the hose 31 is sprung over a nipple 69 formed on a head 70, through which head and nipple there is a passageway 71. This passageway is counter-bored, as shown at 72, and threaded to receive the nipple 56 and the head is formed with an expanded end 73 adapted to the shoulder 55 and confining rubber or other suitable packing 74 thereto. Concentric with the head 70 is an approximately conical cap 75 formed with a hose-receiving end 76 over which the end of the hose 34 is sprung, and the larger end of this cap 75 is threaded to receive the threaded collar 58 on the bell 50, while exterior to the threaded portion of the cap 75 there is formed an annular part 77 adapted to the shoulder 57 and confining a suitable packing ring 78 thereto. The cap 75 and head 70 are formed in one piece and connected by suitable webs 79.

Exterior to the bell 50 at diametrically opposite sides thereof, are bosses 80 from which project lugs 81 terminating in flat heads 82. Adapted to the lugs 81 are eyes 83 on the ends of a yoke 84 receiving a handle 85. The eyes are extended at diametrically opposite points, as shown at 86, so as to receive the heads 82 which lock these eyes onto the lugs 81 when the yoke is inclined at an angle. When the yoke is brought to the upright position then the eyes may be sprung on or off the lugs 81 because the arms of the yoke are made slightly elastic by being reduced in diameter toward the eyes. The

handle 85 may be made of several sections as indicated at 85' in Fig. 6, so that it may be lengthened or shortened to adapt the handle to the convenience of the user and to the position in which the cleaning head is to be used. 70

Now, let it be assumed that the pump is in operation and that air is compressed into the tank 2 and the valve 38 is in position to permit the air to flow from the tank 2 to the nozzle 62. Further, let it be assumed that the bell 50 is in close engagement with the article to be cleaned, whether the same be a carpet or a piece of furniture or some other article. Because of the constricted opening 64 the air jet issues with force and disturbs and loosens the dirt on the material circumscribed by the bell. The air reaching the pump is by way of the chamber 5 and conduit 46 through the passage 32, which communicates with the space between the outer bell 50 and the inner bell 51. There is therefore a return of air through the hose 34 and the dust and dirt constituting the refuse from the article to be cleaned is carried by this return flow of air into the compartment 5 90 where, because of the comparatively large capacity of this compartment, the air flow is very much reduced in speed and the refuse carried by the air is deposited in a large measure upon the baffle plates 12 and 13, 95 while the lighter particles which still are suspended in the air are carried through the screens 19, which being of gradually finer mesh in the direction of flow of the air, remove practically all of the foreign matter in 100 the air. However, to thoroughly cleanse the air water may be placed in the compartment provided therefor, and the air being drawn by the pump will pass through the water and so be cleansed from even the finest particles 105 held in suspension. Thus the air before reaching the pump is most thoroughly cleansed and the parts of the pump are thereby saved from injury which might occur from the scoring imparted to the pump cylinders and valves should particles of grit find their way to the pump. 110

In order that the water contained in the final compartment of the cleansing chamber shall not be splashed about when the reservoir and cleansing chamber are moved from place to place, small blocks of cork or wood or other material capable of floating on the water may be used, such floats being indicated in Fig. 1 at 87. 115

Suppose that compressed air alone is desired, then the valve 39 is opened to the desired extent and the suction of the pump acts to draw air through this valve into the passage 32. If the opening of the valve 39 be large enough and the air jet be strong enough then air coming into the passage 32 will flow out through the valve 39, the pump in the meanwhile sucking from the passage 32 such air as required. However, since the 120 125 130

pump can pump out only as much air as it receives, very little air will flow out of the valve 39, especially as some air will flow under the edges of the bell. If this leak of air 5 under the bell be sufficiently large in quantity, then air will actually flow in through the valve 39. Suppose that the valve 39 be closed and the valve 37 be opened. Then a part of the compressed air from the reservoir 10 2 will flow out of this valve to the atmosphere, the amount of such outflow depending upon the extent of opening of the valve 37. This of course lowers the air pressure at the nozzle 62. Under these conditions it is evident 15 that less air is passing into the cleaning head than the pump is taking out so that there is more or less of a vacuum formed. Since, however, air is flowing to the nozzle 62 the vacuum will not increase above a certain 20 amount while the air jet continues to stir up the dirt on the object being cleaned.

If the straight vacuum process is desired, then the three-way valve 38 is turned to connect 25 the reservoir directly with the atmosphere and to cut it off from the passage 29 beyond the valve. Under these conditions the pump is drawing air through the cleaning head and passage 32 but is delivering air idly to the atmosphere. Now, the only air which 30 can reach the pump must come through the article being cleansed since the vacuum created only serves to seat the edges of the cleaning head firmly upon such object. Under these conditions the vacuum is as high 35 as may be obtained by the apparatus since all the air which passes to the pump must come either through the material being cleansed or around the edges of the cleaning head. But with an apparatus properly constructed 40 the leak under the edge of the rubber flange or washer 68 will be practically nothing.

Since there may be some liability of the valve 39 choking from an accumulation of 45 dust or dirt, this valve may be located in the pipe 20' on the pump side of the casing 5 as shown in Fig. 6, at 39' since at this point the air is clean.

The parts are so proportioned that the passage 50 of air through the depositing compartment 5 is very sluggish giving ample time for the gravitation of the particles to the bottom or for them to cling to the baffle plates without being disturbed by the flow of air.

55 After the device has been used for a time it becomes necessary to clean the deposit chamber or casing 5 from the accumulated refuse removed from the articles cleansed. For this purpose the pipe 21 is disconnected from 60 the nozzle 22 or from the pipe 20, and the latch bolts 7 are moved out of engagement with the flange 6 so that the tank 5 as a whole may be lifted from engagement with the main tank or reservoir 2. Now, by pulling 65 out the bottom plate 10, which may be

done by the use of a suitably located finger ring or other type of handle, the baffle plates 13 may all be removed from the baffle plates 12 and the whole structure is thereby easily cleansed and the water in the water tank may 70 be caused to flow out through the opening 17. When the parts are again put in place fresh water may be poured into the opening 17 and the cap 18 replaced. When the casing 5 is lifted from the tank 2 the flanged conduit 46 75 is lifted from the bell 36, and when the parts are again assembled the flange 48 once more is seated in the bell 36 against the washer 49. A similar structure may be used in connection with the pipes 20 and 23 so that it is unnecessary to disconnect a flexible pipe from the nozzle 22 when it is desired to remove the casing or compartment 5. This is shown in Fig. 6, where the pipe 20' is connected to the pipe 23 by a separable coupling comprising a 80 bell 36' on the pipe 23 while a flange 48' seated therein is formed on the corresponding end of the pipe 20'.

It is to be understood of course that the hose connections 31 and 34 are made as long 90 as may be necessary to permit the cleaning head to be used at an appropriate distance from the pump and depositing tank.

What is claimed is:—

1. In a cleaning apparatus, an air pump, a 95 cleaning head, a conduit between the cleaning head and the intake side of the pump for conducting air from the cleaning head, a conduit between the cleaning head and the pressure side of the pump for conducting air to 100 the cleaning head, and means in each of said conduits to and from the cleaning head for controlling the flow into and exhaustion of air from the cleaning head without affecting the operation of the pump. 105

2. In a cleaning apparatus, an air pump, a cleaning head, a conduit between the pressure side of the pump and the cleaning head, a conduit between the intake side of the pump and the cleaning head, and a valve 110 provided with a port leading to the external atmosphere and adapted to be placed in communication with either of the two conduits at will.

3. In a cleaning apparatus, an air pump, a 115 cleaning head, a conduit between the pressure side of the pump and the cleaning head, a conduit between the intake side of the pump and the cleaning head, a valve provided with a port leading to the external 120 atmosphere and adapted to be placed in communication with either of the two conduits at will, and another valve in the conduit between the pressure side of the pump and the cleaning head, said valve being movable to connect the pump to the cleaning head or to cut off the pump from the cleaning head and connect the pressure side of the pump to the atmosphere. 125

4. In a cleaning apparatus, an air pump, a 130

cleaning head, a conduit between the pressure side of the pump and the cleaning head, a conduit between the intake side of the pump and the cleaning head, a valve provided with a port leading to the external atmosphere and adapted to be placed in communication with either of the two conduits at will, another valve in the conduit between the pressure side of the pump and the cleaning head, said valve being movable to connect the pump to the cleaning head or to cut off the pump from the cleaning head and connect the pressure side of the said pump to the atmosphere, and a valve in the conduit between the cleaning head and the intake side of the pump for coupling the said conduit to the external atmosphere at will.

5. In a cleaning apparatus, an air pump, an air reservoir, a depositing chamber 20 movably connected to and carried by said air reservoir, a conduit between the reservoir and the pump, a cleaning head, a conduit between the cleaning head and the reservoir, a separable conduit between the 25 cleaning head and the depositing chamber and a separable conduit between the said depositing chamber and the pump.

6. In a cleaning apparatus, a pump, a reservoir connected thereto, a cleaning head, a 30 conduit between the intake side of the pump and the cleaning head, an air jet nozzle carried by said cleaning head, a conduit between the nozzle and the reservoir, and a valve movable for connecting the reservoir with 35 the nozzle or the reservoir with the external air at will.

7. In a cleaning system, a pump, an air reservoir, a cleaning head, an air conduit between the cleaning head and reservoir, a 40 valve in said conduit for connecting the reservoir with the cleaning head or with the external atmosphere, another valve for connecting the conduit leading from the reservoir to the cleaning head with the external 45 atmosphere, and a conduit between the cleaning head and the intake side of the pump.

8. In a cleaning apparatus, an air pump, a

reservoir connected thereto, a cleaning head, a jet-nozzle therein, an air conduit leading 50 from the reservoir to the nozzle, valves in said conduit for coupling the reservoir to the conduit or to the external air and for connecting the conduit to the external air, a depositing chamber, a conduit leading therefrom to the intake side of the pump, and another conduit leading from the cleaning head to the depositing chamber.

9. In a cleaning apparatus, an air pump, a reservoir connected thereto, a cleaning head, 60 a jet-nozzle therein, an air conduit leading from the reservoir to the nozzle, valves in said conduit for coupling the reservoir to the conduit or to the external air and for connecting the conduit to the external air, a depositing chamber, an air conduit leading 65 from the cleaning head to the intake side of the pump through and including the depositing chamber, and a valve in the said last named conduit between the cleaning head 70 and the pump and movable to open said last named conduit to the external air at will.

10. In a cleaning apparatus, a cleaning head comprising spaced bells one concentric to the other with the inner bell shorter than 75 the outer bell and with its lower edge above the lower edge of the outer bell, a nozzle connected with the inner bell at the center thereof and perpendicular to the plane of the bottom of the lower bell, means for attaching 80 two concentric hose to the bells one in communication with the nozzle and the other with the interior of the outer bell, and an elastic annular bearing face connected to the bottom of the outer bell.

In testimony that we claim the foregoing as our own, we have hereto affixed our signatures in the presence of two witnesses.
